CLAIM

The ornamental design for a decorative ostomy cover, as shown and described.

DESCRIPTION

FIG. 1 is a perspective view of the decorative ostomy cover present invention depicting how it is worn;

FIG. 2 is a view of the front of the decorative ostomy cover;

FIG. 3 is a view of the back of the decorative ostomy cover;

FIG. 4 is a top view of the decorative ostomy cover;

FIG. 5 is a bottom view of the decorative ostomy cover;

FIG. 6 is a view of the right side of the decorative ostomy cover; and,

FIG. 7 is a view of the left side of the decorative ostomy cover.

The broken lines showing various features in FIGS. 1-7 is included for the purpose of illustrating use and environment and forms no part of the claimed design. This is also true for the wavy broken lines on the fabric which are intended to depict a fabric pattern which is not claimed as part of the present design.
